PROTECTING-SHIELD FOR GUNS.

No. 927,863.

Specification of Letters Patent.

Patented July 13, 1909.

Application filed October 29, 1908. Serial No. 460,133.

To all whom it may concern:

Be it known that we, OTTO LAUBER and HEINRICH KANONENBERG, residing at Essen-on-the-Ruhr, Germany, both subjects of the 5 Emperor of Germany, have invented a certain new and useful Improvement in Protecting-Shields for Guns, of which the following is a specification.

The present invention relates to protecting shields for guns and the object of the invention is to provide the shield with a blind which is adapted to cover the sight opening of the shield and which affords a particularly effective protection against the enemy's 10 fire. In accordance with the present invention, this object is attained by the fact that the blind, which is hinged to the protecting shield, is provided with side walls for the sight-opening, which side walls, when the 15 blind is open, form a lateral protection for the sight-opening.

One embodiment of the invention is shown in the accompanying drawings, by way of example.

25 Figure 1 is a side view of the protecting shield and the parts of the gun to which the invention appertains; Fig. 2 shows a part of Fig. 1, on an enlarged scale; Fig. 3 is a front view of Fig. 2, and Fig. 4 is a section on line 30 4—4, Fig. 2, looking from above.

A indicates the gun barrel which in the known manner is mounted to slide on the slide-track carrier B. The carrier B, on which is arranged the sight device C of the 35 gun, is swingingly mounted in the mount D through the medium of the horizontal trunnions b¹. The protecting shield E is in the known manner secured to the mount D and is provided with an opening e¹ (Figs. 3 and 40 4) for the sighting line of the sight-device C. The blind, which is adapted to cover the sight opening e¹ and which consists of a flap G and two side walls G¹ extending toward the rear side of the protecting shield, is jointed 45 to the protecting shield above the sight opening e¹ through the medium of two hinges F. The side walls G¹, which have substantially the shape of sectors having their center coinciding with the axis of rotation of the 50 blind G G¹, are arranged in such a manner that they can pass through the sight opening e¹ and contact with the side walls of the sight opening when the side walls G¹ are located

within the sight opening. The side walls G¹ extend so far toward the rear side of the 55 shield that they are still located partly behind the shield when the blind is in its uppermost position indicated in dotted lines in Fig. 2. The dimensions of the sight opening e¹ are selected in such a manner that the 60 sighting line passes through the sight opening and between the side walls G¹ in all the positions which the sighting line can assume during the sighting.

In Fig. 1, the sighting line is, by way of 65 example, indicated in two positions designated x x and x¹ x¹. The sighting line assumes the position designated x x when the sighting line is parallel to the axis of the bore of the gun barrel and the latter lies horizontal. x¹ x¹ indicates the position which the sighting line assumes when the gun is directed against a target located in the muzzle horizon at the border of the firing field. One 70 of the side walls G¹ is provided with a plurality of notches g² for a bolt e³ which is under the action of a helical spring e² (Fig. 4). The bolt e³ is guided in a bearing e⁴ secured on the protecting shield E. The bolt e³ is provided with a handle e⁵ by means of which 75 the bolt can be withdrawn from the notches g² against the action of the spring e². When the gun is directed, the blind G G¹ is only opened to the extent required by the appertaining elevation of the sighting line. If, 80 for instance, the sighting line assumes the position indicated by x¹ x¹ the operator, while holding the bolt e³ in its ineffective position by means of the handle e⁵, adjusts the blind in such a manner that the flap G is 85 located only a short distance above the line x¹ x¹ and that one of the notches g² is located in line with the bolt e³ as indicated in dotted lines in Fig. 1. Thereupon the bolt e³ is released and the spring e² causes the bolt to 90 snap into the registering notch g² to secure the blind in the above-mentioned position.

It will be seen from the drawing that, in 95 this position of the blind G G¹, the sight opening of the protecting shield is protected against projectiles falling at an inclination from above, the part of the sight opening which is located above the sighting line being also protected against projectiles which enter approximately horizontally, while the 100 side walls G¹ of the blind protect the sight 105

opening against lateral fire. The blind therefore affords very great protection.

Having thus described the invention, what is claimed and desired to be secured by Letters Patent is:—

1. A protecting shield for guns having a sight opening, and a blind jointed to the shield and having side walls adapted to protect the sight opening against lateral fire.
- 10 2. A protecting shield for guns having a sight opening, and a blind swingingly connected to the shield and adapted to cover the sight opening when in its closed position; said blind having side walls adapted to protect the sight opening against lateral fire when the blind is open.
- 15 3. A protecting shield for guns having a sight opening, a blind for the sight opening swingingly connected to the shield and having side walls adapted to protect the sight opening against lateral fire when the blind is

open, and means for securing the blind in a plurality of positions relatively to the shield.

4. A protecting shield for guns having a sight opening, a blind for the sight opening swingingly connected to the shield and having side walls adapted to protect the sight opening against lateral fire when the blind is open, and means for securing the blind in a plurality of positions relatively to the shield; said means comprising a plurality of notches in one of the side walls of the blind and a spring pressed bolt mounted in the shield and adapted to engage in said notches.

The foregoing specification signed at Bar-
men, Germany, this 29th day of September,
1908.
